UNITED STATES PATENT OFFICE

DARWIN E. STEVENS AND CHARLES E. BROWN, OF DULUTH, MINNESOTA; SAID BROWN
ASSIGNOR TO SAID DARWIN E. STEVENS AND SYLVESTER GEO. STEVENS, BOTH OF
DULUTH, MINNESOTA

VIBRATING STOOL

Application filed May 21, 1931. Serial No. 538,944.

Our invention relates to vibrating stools especially adapted for use in transmitting vibration to the human body for therapeutic purposes.

5 The principal object is to provide a novel, simple, and practical form of floating seat for such a stool to reduce the waste of vibration to a minimum and prevent same from being transmitted otherwise than to the seat.

10 Another object is to produce such a stool which may be conveniently manipulated for application to different parts of the human body.

15 Other objects and advantages of the novel structure and arrangement of parts will appear in the following description of the invention.

20 Referring now to the accompanying drawings, forming part of this application, and 20 wherein like reference characters indicate like parts:

Figure 1 is a central vertical section, partly in elevation, of one of our improved vibrating stools; and

25 Figure 2 is a perspective view of the holding plate.

1 and 2 represent the seat and legs, respectively, of a common bath stool; in this instance there being four legs which are preferably made of sheet metal and carrying removable rubber tips 3 on the lower extremities thereof, which is also common, but in this instance serving to prevent vibration passing to the floor upon which the stool rests.

30 In order to produce the floating or free feature of the seat it is separated from the upper ends of the legs as by a comparatively thick disc of what is known as sponge rubber, 40 illustrated at 4. The legs are turned at right angles at their upper ends forming a flat shelf-like projection or bearing 5 which is usually spot welded or riveted to the under side of the seat, but here bearing against the 45 under face of the sponge rubber disc 4.

The relative spacing and holding of the legs is accomplished by the bracing members 6 intermediate of the legs and spaced above the lower termini thereof, the under edges 50 of these braces being upwardly arched and

covered with a rubber member 7 which has formed integral with the lowermost edge thereof comparatively large corrugations as at 8 for the convenient grasping of the member 6 when the stool is held with the seat 55 against the body for example over the abdomen or stomach for transmitting vibrations thereto.

These members 6 are of sufficient strength and size to prevent the legs from twisting or otherwise becoming disarranged, and the upper angular end 5 of the legs is retained against the under face of the sponge rubber disc 4 as by the thinner sheet of rubber 9 which is placed thereagainst, when the holding plate 10 is attached to the under side of the seat as by the through bolts 11 which extend through the slotted holes 25 in the ends of the portions 14—15, hereinafter described, for holding the motor 12 in place. 60 65 70

This holding plate is substantially circular in form except as to the four opposite sides which come adjacent the ends of the angle portions 5 of the legs where it is straight as at 13, and has a central cut-out 75 portion with the struck up angle members 14—15, the portion 14 of said members being of the proper depth so that when the portions 15 are drawn tightly against the under side of the seat 1 they will hold firmly 80 the circumferential edge of said plate member up against the rubber 9, thus indirectly impinging against the under side of the members 5 of the legs and holding them 85 tightly in position, but permitting the seat to float freely when vibrated.

Now the motor 12, held in position by the bolts 11, depends centrally from the under side of the seat, and, for an activating element, has applied to the armature shaft 16 thereof the metal eccentric disc 17 which is firmly keyed thereto and at one side of the motor field so that as the motor operates a rapid vibration occurs which is transmitted directly to the seat 1. 90 95

Upon two opposite sides of the holding plate are struck out depending lugs 18 providing attaching means for the holding dome 19 which has suitable holes for registration with like holes in the lugs 18 so that when 100

in position surrounding the motor the dome may be fastened to said lugs as by the bolts 20 and may have any number of ventilating holes 21 therein, as desired. However, it is preferred to leave the lower portion of the dome wholly intact that it may catch any oil leakage or other refuse from the motor which might drip therefrom.

It will be noted that we prefer to use a seat member having a central circular depression therein from above filled with cork as at 22, and the entire seat, including the turned down edges thereof, is surrounded by a disc-like resilient cover 23 entirely overlapping the lower edge of the annular flange of the seat, and preferably provided with a bead as at 24 thereupon, so that when the stool is grasped by the hands a convenient and pleasing handhold is afforded.

Having thus described our invention, what we claim and desire to secure by Letters Patent, is:

1. A vibrating stool comprising a seat portion, a vibrating element fixed to the under surface of the seat portion, a resilient disc about the vibrating element and held against the under surface of the seat portion, and legs the upper ends of which are held against the under surface of said disc.

2. A vibrating stool comprising a seat portion, a resilient disc secured to the under surface of the seat, legs the upper ends of which are embedded within said disc, and a vibrating element fixed directly to said seat portion.

3. A vibrating stool comprising a seat portion, a resilient disc held against the under surface of said seat portion, legs the upper ends of which bear against the under surface of said disc, a holding plate fixed to the seat and having a downwardly stepped outwardly extending flange for holding the legs and disc in position, and means for vibrating the seat portion.

4. A vibrating stool comprising a seat portion, a pair of resilient discs abutting each other and held against the under surface of the seat portion, legs the upper ends of which are held between said discs, a holding plate fixed to said seat and having an outwardly extending flange for holding said legs and discs in position, and means for vibrating the seat portion.

In testimony whereof we affix our signatures.

DARWIN E. STEVENS.
CHARLES E. BROWN.
